UNITED STATES PATENT OFFICE.

CHARLES J. BOHRER AND CHARLES E. NACHTRAB, OF TOLEDO, OHIO.

INTERNAL-COMBUSTION ENGINE.

Application filed July 15, 1922. Serial No. 575,166.

To all whom it may concern:

Be it known that we, CHARLES J. BOHRER and CHARLES E. NACHTRAB, residing at Toledo, Ohio, citizens of the United States, 5 have invented certain new and useful Improvements in Internal-Combustion Engines, of which the following is a specification.

The object of our invention is to utilize 10 to the fullest extent possible the energy of gasoline used in internal combustion engines and to do so by a device or instrumentality of extremely simple construction and not easily put out of order. Our invention is applicable to motors using gasoline 15 or liquid fuel that is vaporized regardless of the use that is made by the power produced by the motor, whether for automobile, tractor, air plane, etc. Our invention consists in whatever is defined by 20 or included within the terms or meaning of the appended claims.

In the annexed drawings:

Fig. 1 is a view in longitudinal section 25 of one embodiment of our invention;

Fig. 2 is a section on the line 2—2 of Fig. 1;

Fig. 3 is a detail view in perspective of 30 the rotary, gas-engaging device.

Briefly described our invention is embodied in a rotary device situated in the path of the gas on its way to the motor so that before the gas enters the engine cylinder it will come in contact with such device, and by rotation of the latter produced 35 by the flowing current of gas, the gas will be agitated and so stirred up that it will be so highly vaporized by the time it reaches the cylinder that practically complete combustion will take place within the cylinder, and the power of the gas utilized to a high 40 degree.

Describing in detail what is shown in the drawings, we place within a cylinder, 10, 45 of suitable metal a shaft, 11, at the center thereof, which is supported and journalled in a diametrically extending cross-bar, 12, the shaft having on opposite sides of the cross-bar, collars, 13, that restrain endwise 50 movement of the shaft, the cross-bar 12, being located at substantially midlength of the cylinder 10. Upon the end of the shaft towards the inflowing stream of vapor is a fan, 14, composed of any desired number 55 of blades or vanes set at such an angle that the gas passing over the sides of the vanes

will cause the revolution of the fan and shaft, and at the other end of the shaft there are several radial blades or arms, 15, which by the revolution of the shaft beat or strike 60 against the gas flowing through the cylinder, 10, and impart a whirling and stirring motion thereto that produces or causes vaporization thereof to a high degree. The gasoline flowing between the vanes of the 65 fan is subdivided into numerous small streams and is thereby prepared for the action of the agitating or stirring device. Preferably the arms of the stirring or agitating device are concavo-convex and they 70 revolve with the concave sides forward.

By our invention not only is great saving 75 of gas effected, but with a car having its motor equipped with our invention, the motor can be idled down to a lower speed than can the same motor without it and the motor will run more evenly.

We do not restrict ourselves to any one size of device nor to the application of our invention to any particular style or kind of 80 motor, nor to the number of cross bars for supporting the shaft for one or more may be used, nor to any of the details of construction shown in the drawing.

Merely to illustrate one installation we 85 show in the drawing the device applied to the intake, 16, of a manifold just beyond the carbureter. The diameter of the cylinder, 10, is substantially that of the interior of the intake and at its outer end the cylinder 90 has an outwardly projecting flange, 17, which lies between the carbureter attaching flange, and the intake flange and thereby our said device is securely and yet without any special attaching means held in 95 place. When the carbureter is already in place it is necessary merely to remove it for the insertion of our device into the intake and then to replace the carbureter. When applied our device is invisible and so protected that it can not be tampered with or 100 injured.

A very important advantage from placing our device within the manifold, or beyond the carbureter, is that no disturbance 105 of the usual position of the carbureter is caused such as throwing it further away from the engine or disturbing its proper alinement, which results from the interposition of such a device between the manifold 110 flange and the carbureter. Another important advantage is that the manifold be-

comes in effect the casing of our device so that nothing in the nature of a casing is required beyond the simple cylinder, 10, that is thrust within the manifold intake.

5 What we claim is:

1. As an improvement in internal combustion engines, the combination of a carburetor having the usual position with reference to the intake manifold, a cylinder 10 fitting the intake manifold beyond the carburetor, a shaft within the cylinder, means between the ends of the cylinder supporting the shaft, a rotary device at the end of the cylinder towards the carburetor that is mounted on said shaft and which derives motion from the inflowing current of fuel, and radial arms on the shaft situated beyond said shaft support having concave faces turned in the direction of rotation of said arms, said cylinder having at its end 20 next the carburetor an outturned flange.
- 10 15 20

2. As an improvement in internal combustion engines, the combination of a carburetor having the usual position with reference to the intake manifold, a cylinder fitting the intake manifold beyond the carburetor, a shaft within the cylinder, means 25

between the ends of the cylinder supporting the shaft, a rotary device at the end of the cylinder towards the carburetor that is mounted on said shaft and which derives motion from the inflowing current of fuel, and radial arms on the shaft situated beyond said shaft support having concave 30 faces turned in the direction of rotation of said arms, said cylinder having at its end 35 next the carburetor an outturned flange.

In testimony whereof we hereunto affix our signatures.

CHARLES J. BOHRER.

CHARLES E. NACHTRAB.
